(57) **CLAIM**

The ornamental design for a clear document sleeve, as shown and described.

DESCRIPTION

FIG. 1 is a perspective view of a clear document sleeve; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of the clear document sleeve in an alternate state; FIG. 10 is an enlarged view of portion 10 shown in FIG. 1; and, FIG. 11 is an enlarged view of portion 11 shown in FIG. 2. The dash-dash broken lines in the drawings depict portions of the clear document protective sleeve that form no part of the claimed design. The dot-dash broken lines represent boundaries of the enlarged portions and form no part of the claimed design.

1 Claim, 11 Drawing Sheets
